FOREIGN PATENT DOCUMENTS

JP 2016260 1/1990

* cited by examiner

Primary Examiner—Catherine R Oliver

(74) Attorney, Agent, or Firm—Laura M. Hagan; Kerrick,
Stivers, Coyle + Van Zant, PLC(57) **CLAIM**

I claim the ornamental design for a “corner post,” as shown and described.

DESCRIPTION

FIG. 1 is a perspective view of a corner post;

FIG. 2 is a perspective view of a corner post, shown fragmented, indicating indefinite length for covering a corner of a structure;

FIG. 3 is a right-side, front elevational view of the one-piece corner post, the left side front elevational view being a mirror image thereof;

FIG. 4 is a left-side, rear elevational view of the one-piece corner post, the right side rear elevational view being a mirror image thereof;

FIG. 5 is a top plan view of the decorative corner post; and,

FIG. 6 is a bottom plan view of the one-piece corner post.
